JUICE EXTRACTOR

Evelyn L. Nesbitt, Los Angeles, Calif.

Application December 14, 1953, Serial No. 28,057

Term of patent 14 years

(Cl. D89—1)

To all whom it may concern:

Be it known that I, Evelyn L. Nesbitt, a citizen of the United States, residing at Los Angeles, in the county of Los Angeles and State of California, have invented a new, original, and ornamental Design for a Juice Extractor, of which the following is a specification, reference being had to the accompanying drawing, forming part thereof.

Fig. 1 is a top plan view of a juice extractor showing my new design;

Fig. 2 is a cross-sectional view taken along line 2—2 of Fig. 1; and,

Fig. 3 is a side elevation view thereof.

I claim:

The ornamental design for a juice extractor, substantially as shown.
